DISHWASHING APPARATUS

Guido E. Barozzi, Woodcliff, N. J.

Application October 27, 1933, Serial No. 695,476

3 Claims. (Cl. 141—9)

The invention relates to dish washing apparatus and has for its object to provide an apparatus of the indicated type which is simple in construction and of maximum efficiency in operation.

5 The invention contemplates further the provision of a dish washing apparatus which may be readily placed in the conventional sink and operatively connected with the customary water faucet and which includes hydraulic means whereby 10 cleansing water is directed against or sprayed over the dishes to be washed and whereby a part of the water is effective to coincidentally bring about a movement, and preferably a rotative travelling movement of said dishes during the 15 spraying thereof.

Other more specific objects will appear from the description hereinafter, and the features of novelty will be pointed out in the claims.

Reference is to be had to the accompanying drawings which illustrate an example of the invention without defining its limits, and in which Fig. 1 is a plan view of the dish washing apparatus; Fig. 2 is a sectional view on the line 2—2 of Fig. 1, and Fig. 3 is an exterior elevation of 25 said apparatus.

The apparatus comprises essentially a suitable support on which a carrier for the dishes to be washed is movably mounted in operative relation to a combined actuating and spraying means 30 whereby said carrier is movably operated and the dishes thereon are coincidentally sprayed or otherwise subjected to the cleansing action of the water. In the illustrated example, the support comprises an upright container having an 35 outlet at its lower end through which the soiled waste water may escape, said container consisting of an outwardly and downwardly sloping bottom member 5 preferably of concavo-convex form provided with a peripheral flange 6 whereby 40 the apparatus is supported in an upright position on the bottom 7 of a conventional sink or any other equivalent supporting surface. In its illustrated form, the support further includes a hollow shell 8 preferably of cylindrical shape and 45 supported at a distance above the bottom member 5 in axial and preferably conterminous registry therewith by means of a plurality of lugs 9 or the like, as shown in Figs. 2 and 3; with this arrangement, the space between the lower edge 50 of the shell 8 and the peripheral edge of the bottom member 5 constitutes an annular exit opening 10 through which the soiled waste water escapes, for instance, to the sink. The upper end 55 of the shell 8 is preferably closed by means of a cover 11 suitably fixed in position, said shell

having an opening for the introduction and removal of the dishes, which is normally closed by a suitable closure such as the hinged doors 12 illustrated in Figs. 1 and 3. The construction and arrangement is such that with the doors 12 in the closed position illustrated in Fig. 3, the shell 8, or in other words, the container is watertight, excepting at the bottom where the annular opening 10 or its equivalent permits the waste water to flow from the interior thereof. The apparatus further includes a carrier which is movably mounted within the container or shell 8, which carrier, in the illustrated example, is composed of a plurality of superimposed shelves 13 fixed upon a shaft 14 and secured in spaced relation by strengthening rods 15, as shown in Fig. 2. To facilitate the rotation of the aforesaid carrier, the shaft 14 has its opposite ends journaled in ball bearings 16 located in bearings 17 mounted respectively upon the bottom member 5 and the cover 11. The shelves 13 may be provided with suitable devices for retaining the dishes in the most efficient position thereon for cleaning, the illustrated example showing bars 18, dish and plate racks 19, saucer and dessert racks 20, cup racks 21 and tumbler and glass spindles 22, as examples of the devices in question.

In addition to the parts so far described, the apparatus includes a means which operates to rotate the aforesaid carrier and to coincidentally spray or otherwise direct cleansing water into contact with the dishes to be washed. In the illustrated example, this means comprises a rotor 23 mounted upon the shaft 14 and provided with a plurality of blades 24 against which water is directed by a jet nozzle 25, which forms the terminus of one end of a pipe 26, the other end of which is connected with a pipe 27 extending lengthwise of the shell or container 8 in operative relation to the carrier 13—14. At its lower end, 40 the pipe 27 projects exteriorly of the container or shell 8 and terminates in an external water connection 28 adapted to accommodate a hose 29 arranged to be connected with the customary water faucet of the aforesaid conventional sink 45 or to receive a corresponding permanent water connection leading to an equivalent source of water supply. The pipe 27 at intervals throughout its length is provided with jet apertures or spray nozzles 30 which preferably are arranged 50 to develop sprays in different directions inwardly toward the carrier 13—14, as diagrammatically illustrated in Fig. 2. Suitable locking means 31 may be provided for maintaining the previously mentioned doors 12 in their closed position. 55

In utilizing the apparatus, it may be placed, for instance, in an upright position upon the bottom 1 of a conventional sink and connected by means of the hose 29 with the faucet of the aforesaid conventional sink. By adjusting the doors 12 to their open position, the dishes to be washed may be placed upon the individual shelves 13, for instance, in the manner indicated in Fig. 2, after which the doors 12 are closed and locked and the water supply turned on. This water supply passes upwardly through the pipe 27 and in part issues from the openings or nozzles 30 in the form of jets or sprays, which contact with the dishes on the platforms 13, and subject the same to a cleansing and washing action; at the same time, a portion of the water passes into the pipe 26 to the jet nozzle 25 whereby it is directed against the blades 24 and thus causes the rotor 23 to be rotatively actuated, as will be apparent. The carrier 13—14 with the dishes thereon is thus rotated within the container or shell 8 coincidentally with the spraying of the dishes on the platforms 13, so that said dishes are subjected to a most thorough and efficient cleansing and washing. In addition to this, the water from the jet 25, after it has functioned to actuate the rotor 23, drips downwardly therefrom and subjects the dishes on the platforms 13 to a shower of water from above, which augments the cleansing action of the jets or sprays issuing from the openings or nozzles 30.

The water after it has been directed against the dishes on the platforms 13 passes downwardly to the bottom member 5 and because of the downwardly and outwardly sloping form thereof is directed toward the exit opening 10 through which it flows as waste water into the sink and from thence through the customary drain to the sewer. If the apparatus is otherwise supported than upon the bottom of a conventional sink, suitable provision will be made for receiving and disposing of the waste water which issues from the exit opening 10.

The apparatus is extremely simple in construction and is automatic in its operation, and after it has performed its cleansing functions may be utilized to thoroughly rinse the dishes with clean water and as a drying rack in which the thoroughly cleaned dishes may be permitted to dry.

The completely dried dishes may then be removed from the apparatus by simply opening the doors 12 whereby the interior of the container or shell 8 is rendered readily accessible. The apparatus may be of minimum weight, so as to be capable of being easily handled and transported, and is of such a nature that it is not likely to become disarranged or inoperative. If desired, suitable provision may be made to facilitate the transportation of the apparatus from one place to another. It will be obvious that the apparatus may be permanently connected with a suitable source of cleansing water, and that it may be constructed in any suitable shape and in any dimensions to provide the capacity desired. Likewise, any suitable material may be utilized in its construction.

Various changes in the specific forms shown and described may be made within the scope of the claims without departing from the spirit of the invention.

I claim:

1. In a dishwashing apparatus, that improvement which comprises a bottom member sloping downwardly and outwardly from its center toward its periphery, and a hollow upright enclosing shell corresponding in cross-sectional form to the shape of said bottom member and supported on said bottom member in conterminous relation thereto and at a distance therefrom to provide an exit opening at the periphery of said sloping bottom member for the escape of water waste.

2. In a dishwashing apparatus, that improvement which comprises a hollow container having an annular exit opening at its lower end for the escape of water waste, and an upwardly arched bottom for said container in conterminous relation thereto sloping downwardly and outwardly from its center toward said annular exit opening.

3. In a dishwashing apparatus, that improvement which comprises a cylindrical hollow container having a continuous circumferential exit opening at its lower end for the escape of water waste, and a bottom for said container corresponding in shape to the cross-sectional form of said container sloping downwardly and outwardly from its center toward said exit opening.

GUIDO E. BAROZZI.
